UNITED STATES PATENT OFFICE.

ISIDORE P. SMITH, OF TOLEDO, OHIO, ASSIGNOR TO THE HETTRICK MANUFACTURING COMPANY, OF TOLEDO, OHIO, A CORPORATION OF OHIO.

HUNTING COAT.

Application filed November 26, 1928. Serial No. 321,899.

This invention relates to clothing, but more particularly to coats, vests and the like used for hunting and fishing, and an object is to provide a simple and efficient garment 5 of the above type having a relatively deep pocket for game or fish which is readily accessible, may be entirely opened for inspection and cleaning, and lends itself admirably for commercial production. Other 10 objects and advantages will hereinafter appear.

The invention is shown by way of illustration in the accompanying drawings, in which:

15 Fig. 1 is a view of a hunting coat spread out to show the inside thereof;

Fig. 2 is a fragmentary detail showing a portion of the game pocket fully opened;

Fig. 3 is a section on the line 3—3 of 20 Fig. 2; and

Fig. 4 is a detail showing another manner of connecting the sides of the pocket to the coat.

The illustrated embodiment of the invention 25 comprises a hunting coat 1 of canvas or other suitable material, and as the body of the coat is of conventional design, detail description thereof is not considered necessary. An important feature of this invention consists in the provision of a pocket 30 which extends from one side of the coat to the other.

As shown, the pocket consists of a piece 2 of fabric, such as canvas, which extends 35 from the button-hole strip 3 to the button-carrying strip 4. The width of the piece 2 is considerable, and may be about one-half the vertical length of the coat in order to provide a spacious pocket for game. Forming 40 a protecting coating for the fabric piece 2, is a water-proof fabric piece 5, such as rubberized canvas, and this piece is disposed on the inside of the fabric piece 2. This arrangement is particularly advantageous 45 because the fabric piece 2 is kept dry, and furthermore, the surface of the piece 5 is such that it may be readily washed and scoured after the game or fish have been removed from the pocket.

50 The fabric piece 2 and water-proof piece 5 are sewed to the marginal edge by twin rows 6 of stitching, which are usually employed as a binder for the lower edge of the coat body. It will be understood that ordinarily the lower edge of the coat body is

folded upwardly and stitched for reinforcing purposes and to prevent raveling, so that in the manufacture of this coat no additional sewing operation is required.

The sides of the pieces 2 and 5 may be 60 detachably connected to the coat body by fastening means 7 having an interlocking slide 8. Such fastening means are usually referred to as "zippers", and are well known; detail description is not considered necessary. It is desirable that the side edges of the pocket be detachable to afford complete access to the inside, and thereby eliminate troublesome and disagreeable groping in a dark pocket, although an important feature resides in the ability to thoroughly clean the pocket throughout. If desired, lacing 9 may be used to advantage instead of zippers, and although these means for attaching the sides of the pocket are shown, 70 other equally satisfactory means may be resorted to. It will be apparent that the elongated piece 2 extends from adjacent one free vertical side edge to a point adjacent the other free vertical side edge. The coat shown is conventional in general formation. The free vertical side edges providing the usual fastening means for connecting the free portions. 80

Secured to the upper marginal edges of the fabric pieces 2 and 5 are fastener members 10 detachably engaging complementary members 11 attached to the inside of the coat body. In this instance, five fasteners are arranged in spaced relation on the coat body 90 and fabric pieces. These fasteners are adapted to support the load carried by the pocket, and are arranged to distribute the strain. 85

From the above description, it is manifest 95 that the pocket may be readily opened by disengaging the fastener members 10 and 11 to permit access to the inside. After game or fish are removed from the pocket, the sides of the pocket can be released to allow 100 thorough cleaning of the pocket. A valuable feature resides in the ability to sew the pocket to the coat without any operation substantially different from the usual manner of manufacturing similar coats without 105 the above improvements.

Although the invention has been described in connection with a hunting coat, it is not so limited. Numerous changes in details of construction and arrangement may 110

be effected without departing from the invention, especially as defined in the claim.

What I claim as new and desire to secure by Letters Patent is:

8 A hunting coat comprising a body having free vertical side edges, an elongated fabric piece extending from one side edge of the body to the other side edge, stitching securing the lower marginal portion of the

piece to the body, detachable fastening 10 means intimately connecting opposite side edge portions of said piece to the body, and detachable supporting fasteners connecting the upper marginal portion to the body.

In testimony whereof I have hereunto 15 signed my name to this specification.

ISIDORE PETER SMITH.
